Robert M. Fenner and Donald E. Hamilton, both of
3200 S. Zuni St., Englewood, Colo.

Filed Dec. 10, 1965, Ser. No. 140

Term of patent 14 years

(Cl. D45—19)

FIG. 1

FIG. 2

FIG. 3

FIG. 1 is a front elevational view of a lapel pin, showing our new design;

FIG. 2 is a side elevational view thereof; and

FIG. 3 is a rear elevational view thereof, the broken line showing of the pin clasp having been omitted for convenience of illustration.

The dominant features of our design reside in the full line portions of the drawing.

We claim:

The ornamental design for a lapel pin or similar article, as shown and described.
